CLAMPING MECHANISM

Cyril M. Andrews, University City, Mo., assignor
to Wagner Electric Corporation, St. Louis, Mo.,
a corporation of Delaware

Application April 4, 1935, Serial No. 14,609

7 Claims. (Cl. 90—59)

My invention relates to a clamping mechanism, one of the objects being to provide a device for clamping to a support, with equal pressure and by a single operation, a plurality of castings or the like which have varying dimensions.

Another object of my invention is to produce a hydraulically actuated mechanism for the purpose stated.

Other objects of my invention will become apparent from the following description of a single embodiment taken in connection with the accompanying drawings in which Figure 1 is a top view of my clamping mechanism as used on a milling machine; Figure 2 is a side view of the structure shown in Figure 1; Figure 3 is a partial cross-sectional view on the line 3—3 of Figure 1, showing a fluid motor and clamp; Figure 4 is a cross-sectional view on the line 4—4 of Figure 1, showing one of the compressors.

In the drawings I have shown my invention applied to a milling machine for clamping a plurality of castings of varying size to a supporting table for milling operations, but it is to be understood that the invention may be equally well applied to other machines wherein it is desired to clamp a plurality of articles of varying size to a support.

Referring to the drawings, the table 1 of the milling machine carries two batteries of my novel clamps. Figures 1 and 2 show only one of the batteries, there being a duplicate battery positioned on the opposite side of the table. Only one battery of clamps will be described in detail. The table is adapted to be pivotally mounted upon a post 2 carried by the milling machine base, and is provided with a pair of bearings 3 for a rotatable shaft 4. This shaft is irregular in cross-section and the bearings 3 are received in annular grooves in the shaft, as shown in Figure 2. The shaft 4 carries a plurality of fluid motors, each comprising a cylinder 5 and a piston 6. A piston rod 7 extends through an opening in the base of each cylinder, and a spring 8 surrounds the piston rod for maintaining the piston in retracted position. A suitable packing cup 9 prevents leakage between the piston and the cylinder wall. The open end of each cylinder is closed by a screw plug 10.

The table 1 has pivoted thereon adjacent the shaft a plurality of clamping members 11, there being a clamping member for each cylinder and piston combination carried by the shaft. The clamping member is formed with an extended portion 11¹ which is adapted to be engaged by the piston rod 7 when the clamp is to be operated.

Each clamping member is also provided with another extended portion 12 for co-operation with the element to be clamped, such element in this instance being shown as a cylinder casting 13. The table 1 is provided with suitable supports 14 for receiving the castings, these supports taking the form of upstanding posts which are received in the bore of the cylinder casting. The portion of the cylinder casting which is to be milled is the flat integral extension 15.

The rotatable shaft 4 also carries two compressors 16, each comprising a cylinder 17 and a co-operating piston 18 having a suitable packing cup 19. The pistons of the compressors are adapted to be actuated by set screws 20 threadedly co-operating with the closure plates 21 of the cylinders. The compressors 16 are in communication with each other and with each of the fluid motors by passages 22 extending through the shaft.

The table also has fixed thereto a pair of plates 23 which form bearings for the ends of shaft 4. One end of the shaft has formed therein a passage 24 by means of which the system may be filled with a suitable liquid, this passage being closed by a plug 25. The other end of the shaft has formed therein a passage 26, which is controlled by a screw plug 27, the purpose of which is to permit bleeding of the system so that any air therein may be eliminated when the system is filled.

Shaft 4 is cut away as shown at 28 in order to permit the portions 11¹ of the clamping members 11 to swing downward when the shaft 4 is rotated through a pre-determined angle. Thus the clamping members may be moved clear of the cylinder castings to permit the castings to be readily removed from their supports.

In the operation of my clamping device, the system is filled with a suitable liquid and all the air therein eliminated. When the device is in its inoperative position, the shaft 4 will be in a position wherein the piston rods 7 are out of engagement with the clamping members 11 and the set screws for the compressors are backed off from the pistons 18. By swinging the clamping members away from the supports 14, the cylinder castings, which are of varying dimensions, may be readily placed on their supports 14. The clamping members may now be moved to engage the casting and then the shaft 4 rotated in a counter-clockwise direction and to a position where the piston rods 7 are beneath the clamping portions 11¹. The set screws of the compressors are now screwed down, thereby forcing liquid 55

under pressure into the cylinders 5, and causing the pistons 6 and the piston rods connected thereto to exert pressures on the clamping members and clamp the castings 13 rigidly to their supports. Regardless of the variations in the dimensions of the cylinder castings, each casting will be clamped to the support by an equal pressure. With the cylinder castings clamped in this position, the table 1 is now swung about post 2 and through 180 degrees and rigidly fastened to the base of the milling machine by means of the openings 29, which are adapted to receive suitable spring pressed pins (not shown). The cutting elements of the milling machine may now be brought across the cylinder castings, thereby milling the surfaces 14 on the castings.

To remove the castings from the clamping machines, the liquid under pressure in the fluid motors is released by unscrewing the set screws 20 of the compressors. The fluid motor pistons 6 will be moved to their retracted position by the springs 8. The shaft 4 is now free to be rotated in a clockwise direction (shown by the arrow in Figure 3), thus moving the piston rods from beneath the clamping portions 11. The clamping members are now free to be swung away from the castings, whereby the castings can be readily removed from their supports.

Since the table 1 is provided with two batteries 30 of clamping members, the castings which are held by the opposite battery of clamps (not shown) may be removed and unmilled castings substituted therefor while the milling operation is being performed on the castings held by the 35 first battery of clamps.

The two compressors 16 may, if desired, be replaced by a single compressor of larger size. However, by employing two compressors, the size of the shaft 4 can be held to a minimum. When 40 two compressors are used one may be employed to initially displace the fluid in the system and bring the clamps into contact with the castings, and the other compressor may be employed to apply the clamping pressure to the clamps.

Having fully described my invention, what I 45 claim as new and desire to secure by Letters Patent of the United States is:

1. In a machine for clamping a plurality of members to a support, a movable clamp for operating with each member to be clamped, a rotatable member, a plurality of fluid operated motors carried by the rotatable member, each adapted to operate a clamp, a fluid compressor carried by the rotatable member and operatively 50 connected with each fluid motor, and means for operating said compressor to apply an equal pressure to each clamp, said motors being adapted to be moved out of operative position with respect to the clamps when the rotatable member 55 is rotated a predetermined distance.

2. In a clamping mechanism, a support, a pivoted clamp on the support for clamping a member to the support, a fluid motor operatively connected to the clamp to apply pressure thereto, a 60 compressor in communication with the motor,

and a rotatable member for carrying the motor and the compressor as a unit, said motor being adapted to be operatively disconnected from said clamp by the rotation of said rotatable member whereby said clamp may be pivotally moved to 5 permit insertion and removal of the member to be clamped.

3. In a machine, a support, a battery of pivoted clamps on the support for clamping a plurality of members to the support, a member movable on the support, a plurality of fluid motors carried by the movable member, and means comprising a fluid compressor mounted on the movable member and in communication with each motor to apply equal pressure to each clamp, 10 15 said fluid motors being operably disconnected from the clamps by movement of the movable member.

4. In a clamping machine, a battery of clamps, a rotatable member, a fluid motor for each clamp 20 and carried by the rotatable member, a fluid compressor carried by the rotatable member, conduits in said rotatable member for connecting the compressor with each motor and means for disconnecting each motor from its clamp by rotating the rotatable member through a pre-determined angle.

5. In a clamping mechanism for clamping a plurality of members to a support, a plurality of pivoted clamps, a rotatable member, a plurality of fluid motors carried by the rotatable member for operating the clamps, a compressor carried by the rotatable member and comprising a piston and a cylinder in communication with all of the fluid motors, and a set-screw for moving the 35 piston of the compressor, said motors being adapted to be moved as a unit out of operative engagement with the clamps when the rotatable member is rotated through a predetermined angle.

6. In a clamping mechanism, a support, a movable clamping element on the support for clamping a member to the support, a rotatable member, and fluid operated means carried by and movable with the rotatable member and adapted to be connected with the clamping element for 40 applying pressure to said element, said fluid operated means being movable out of operative relation with the clamping element by rotation of the rotatable member whereby the member to be clamped may readily be inserted and removed.

7. In a clamping mechanism, a plurality of separate clamps each embodying a movable element, the movable element of each clamp being capable of movement independently of movement of the movable elements of other clamps, 55 a movable member, fluid motors for operating the movable elements of the clamps, there being a motor for each clamp and said motors being mounted on the movable member, said motors being operatively disconnected from the movable elements by movement of the movable member, and a fluid compressor in communication with the motors for operating said motors simultaneously.

CYRIL M. ANDREWS. 65
